[57] CLAIM

The ornamental design for an electronic console for the
remote control of burglar, smoke alarms and the like,
substantially as is shown and described.

DESCRIPTION

FIG. 1 is a front perspective view of an electronic console
for the remote control of burglar, smoke alarms
and the like showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.

FIG. 1

FIG. 2

FIG. 3

FIG. 4

FIG. 5

FIG. 6

FIG. 7
